UNITED STATES PATENT OFFICE.

RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

ELECTROMAGNETIC DEVICE.

1,320,247.

Specification of Letters Patent. Patented Oct. 28, 1919.

Application filed March 28, 1916. Serial No. 87,191.

To all whom it may concern:

Be it known that I, RICHARD C. LEAKE, a citizen of the United States, and a resident of the city of Rochester, in the county of Monroe and State of New York, have invented a new and useful Electromagnetic Device, of which the following is a specification.

This invention relates to an electro-magnetic device and more particularly to an electro-magnetic device known as a relay.

The primary object of this invention is to so construct a relay that a definite and relatively prolonged period will elapse after its energization or deenergization before the circuits controlled thereby are altered from opened to closed or vice versa.

A further object of the invention is to so construct a relay of the type specified, that the circuits controlled thereby will after the lapse of the definite and relatively prolonged period be quickly opened or closed.

Other objects and advantages will appear as the description of the invention progresses, and the novel features of the invention will be pointed out in the appended claims.

In describing the invention in detail, reference is had to the accompanying drawings, wherein like characters of reference designate corresponding parts throughout the several views and in which:

Figure 1 is a front elevational view, showing the deenergized position of a relay embodying the invention with the front cover removed and certain parts broken away to more clearly show the construction; Fig. 2 is also a front elevational view but shows the parts in their energized position, the parts broken away in Fig. 1 being shown in Fig. 2 in full; Fig. 3 is a partial vertical section taken on the line 3—3 of Fig. 1, viewed in the direction of arrow *a*; Fig. 4 is a vertical section taken on the line 4—4 of Fig. 3 viewed in the direction of arrow *b*; Fig. 5 is a vertical section taken on the line 5—5 of Fig. 3, viewed in the direction of the arrow *c*; Fig. 6 is a sectional plan view taken substantially on the line 6—6 of Fig. 3 viewed in the direction of arrow *d*.

The relay consists generally of a casing A, circuit controlling mechanism B and a motor C.

The casing A consists generally of two parts, best shown in Fig. 3, a main body

portion 2 and a cover 4. The cover 4 is firmly attached to the casing 2 in any well known and approved manner as by screws, which may pass through the cover 4, and into threaded holes 6, best shown in Fig. 1. 60 Between the main body 2 and the cover 4 is placed a gasket 7 which renders the joint watertight. The cover 4 is formed with a large opening in which is placed a pane of glass 8 so that the mechanism within the 65 casings may be readily inspected from without. The glass 8 is held in position by pins 9 and clips 10 best shown in Fig. 3.

Since the motor forms no part of this invention, it is not shown in detail and it 70 may be of any suitable or well known construction and is arranged to rotate shaft 11 in one direction when it is set in operation. The motor is preferably mounted in protecting casing C. 75

Referring to Fig. 3, a shaft 11 driven by the motor has a collar 12 fastened thereto by means of a pin 13 best shown in Fig. 6. Mounted loosely on shaft 11 is a sleeve 14 on which are fixed a pinion 15 and a ratchet 80 wheel 16. Between the collar 12 and the sleeve 14 is a fiber washer 17 and at the opposite end of sleeve 14 is another fiber washer 18, and bearing against washer 18 is another washer 19¹ into which is loosely 85 pressed one end of a sleeve 19. Encircling sleeve 19 is a spring, one end of which bears against the enlarged portion of sleeve 19 and the other end against washer 19¹, which spring presses sleeve 14 against collar 12, 90 making it difficult for the pinion 15 and the ratchet wheel 16 to move independently of the shaft 11 but avoiding unnecessary shocks to the motor for the reason that when the mechanism reaches the limits of its movement and is abruptly stopped, the motor is allowed to come to a gradual stop due to the slipping of the motor shaft 11 in its clutch. Mounted on the sleeve 14, but free 95 to turn thereon, is an escapement wheel 21. 100 Bearing on the teeth of the ratchet wheel 16 are pawls 22 which are pivotally fastened to the escapement wheel 21 by means of pins 23 and which have their outward movement limited by stop pin 67 fixed in the 105 escapement wheel 21. On one side of the case 2 best shown in Fig. 3 is a lug 24 having a bushing 25, screw threaded therein, which forms one bearing for shaft 26, and the other bearing for said shaft is formed in 110

like manner in a lug 27 on the opposite end of casing 2 best shown in Fig. 5. Mounted on the shaft 26 and adapted to rock thereon is a pallet support 28, one arm of which 5 has a U shaped end 28¹ and supports the pallet 30 by means of pivot pin 31 and the bearings 32 and 33 which are screw threaded in the U shaped end 28¹ of the pallet support 28. Each end of the pallet 30 best 10 shown in Figs. 1, 2 and 5, is weighted and on its lower edge are two teeth 30¹ and 30² which are adapted to engage with the teeth 21¹ of the escapement wheel 21 and co-operate therewith in a manner which will 15 be hereinafter more fully described.

A counterweight 34 is fixed to the shaft 26 and has, on its periphery, teeth 34¹ which mesh with teeth on a pinion 35, the shaft 36 for which is mounted in the bearings 37 and 20 38 which are screw threaded in lugs 39 and 40 respectively formed integral with the casing 2, best shown in Fig. 3.

Fixed in and projecting from both sides of the counterweight 34 is a pin 44, best 25 shown in Fig. 3. One end of pin 44 moves in the slot 45¹ of a link 45 and the other end strikes the arm 28² of the pallet support 28 and lifts the pallet 30 out of engagement with the teeth 21¹ of the escapement wheel 30 21 after the counterweight has moved up to a certain point, which will be hereinafter more fully explained. The pallet 30 is limited in its upward movement by pins 46 which are mounted in the casings 2 and are 35 best shown in Fig. 5.

The pallet support 28 is spring pressed downwardly by a spring 47 which bears against the vertical arms 28³ and 28⁴ of the pallet support 28, the movement of said 40 arms being limited by the head 48¹ of the stop bolt 48. It will be readily seen by referring to Figs. 1, 4 and 5 that if the stop bolt 48 is adjusted either in or out, that the pallet 30 will be correspondingly raised or 45 lowered in its relation to the teeth 21¹ of the escapement wheel 21 and when the pallet 30 has been once adjusted to its proper position, the stop bolt 48 may be locked by screwing down the jam nut 49 against the lug 50 of 50 the casing 2.

On the left hand side of Fig. 1 is a stop arm 52 which is mounted loosely on a bearing stud 51, supported by the lugs 24 and 27 of the casing 2. Referring to Figs. 1 and 55 4 it will be seen that at the lower end of stop arm 52 is a projecting portion 52¹ that bears against a side of the counterweight 34 and acts as a stop therefor. The adjusting screw 53, screw threaded in the lug 54 of the 60 casing 2 bears against the stop arm 52 and it may readily be seen, by referring to Figs. 1 and 4, that adjusting the screw 53 in or out will turn the stop arm 52 on its bearing and correspondingly raise or allow the 65 counterweight 34 to lower. When the stop

arm has been adjusted the screw 53 may be locked in position by screwing down the jam nut 55 against lug 54. As a result of the raising or lowering of the counterweight 34, it will be seen by referring to Fig. 4 that 70 the pin 44 will be brought either nearer to or farther away from the arm 28² of the pallet support 28, and will also be correspondingly raised or lowered in the slot 45¹ of the link 45, and in this way the timing of 75 the opening and closing of the contacts is accomplished, as will be hereinafter more fully explained.

To facilitate the adjustment of the timing parts, a scale may be marked on the counterweight 34 in any convenient manner and a pointer to register with said scale may also be conveniently placed as for example on bearing screw 37, thus it will be apparent that after the calibration had been once 80 made on a relay, changes in adjustment could be rapidly made.

Referring to Fig. 1, contact carrier 56 is mounted on the pin 57 which is secured in a lug 58 of the casing 2. The said contact carrier 56 has on its left hand side a counterweight 56¹, which tends to rock it to the left, on its pin 57 thus causing the contact fingers 59, which are insulatedly fixed to the contact carrier 56, to be moved to the left and at their upper ends to co-operate with insulated contacts 61 of binding posts 62 which are securely mounted in the top of casing 2.

The link 45 is loosely fastened at one end 100 of the contact carrier 56 by pin 63 and having at its other end a slot 45¹, adapted to move freely on the pin 44 for part of the movement of the counterweight 34 and to be lifted by the pin 44 of the counterweight 34 105 for the balance of its movement, thus it will be seen by referring to Fig. 2 that the contact carrier 56 will be rocked on pin 57 and the contact fingers 59 will break contact with contacts 61 and will make contact with 110 insulated contacts 64 of the binding posts 65 which are also securely insulatedly mounted in the top of casing 2. The upward movement of the contact carrier 56 is limited by the stop 66 of the casing 2. In the top 115 of the casing A is an adjustable stop pin or screw 68 which limits the upward movement of the counterweight 34.

Fig. 1 shows the parts in the deenergized condition of the relay, the pallet support 28 being properly adjusted in relation to the teeth 21¹ on the escapement wheel 21 by means of adjusting screw 48, and the stop arm 52 being adjusted to bring pin 44 in the proper relation to arm 28² of pallet support 28, to consume a predetermined length of time in its travel.

If energy is applied to the motor it will turn the shaft 11 in the direction of the arrow x Fig. 1. The pinion 15 and the ratchet 130

16, being frictionally mounted on the motor shaft 11 will turn with it, the pinion transmitting motion through the intermediate gears 41, 42 and 43 respectively to the pinion 35 which in turn meshes with the teeth on the counterweight 34, causing it to be raised; and since the teeth on the ratchet wheel 16 engage the pawls 22, the escapement wheel 21 is turned in the direction of the arrow x .

10 The teeth 21¹ on the escapement wheel 21 are equally spaced, one side being radial and the other side having an inclined face and constructed so as to ride on the teeth 30¹ and 30² of the pallet 30, so that as the 15 escapement wheel 21 turns in the direction of the arrow X, the pallet 30 will be rocked on its pivot pin 31 and the teeth 30¹ and 30² will be positively moved in and out of engagement with the teeth 21¹ of the escapement 20 wheel 21. In general the escapement is similar to any well known type. It will be readily seen by referring to Fig. 1 that as each tooth has to lift alternately both sides of the pallet 30 out of engagement 25 with the teeth 21¹ of the escapement wheel 21, a certain amount of work has to be done and the rotation of the mechanism is to that extent retarded.

After the counterweight 34 has been 30 raised by the rotation of the motor, through the medium of the gears, before mentioned, to a certain point, by referring to Fig. 4 it will be seen that the rearwardly projecting end of the pin 44 on counterweight 34 35 will strike the arm 28² of the pallet support 28 and the continued movement of the counterweight will lift the pallet 30 out of engagement with the teeth 21¹ of the escapement 40 wheel 21 and allow the motor and gear train to complete the movement of counterweight 34 to its final position in contact with adjustable stop 68 unimpeded by the pallet 30.

When the counterweight 34 is raised, the 45 forwardly projecting end of the pin 44 will move freely in the slot 45¹ of the link 45 until pin 44 engages the top of slot 45¹ which occurs just previous to the time pallet 30 is raised after which it will lift link 45 50 and rock contact carrier 56 on its pivot pin 57 and the contact fingers 59 will break contacts 61 and make contact with contacts 64, as shown in Fig. 2. It will be noted that the fast completion of the movement, 55 not only assures a quick break and make of the contacts, but also reduces the sparking between the contacts and thus avoids pitting of the contacts.

Assuming that the relay is in the energized position, as shown in Fig. 2, and that 60 energy is removed an initial kick will be given to the counterweight 34 by the spring 47 which bears against the pallet support 28, an arm of which coacts with pin 44 of 65 the counterweight 34, thus it will be appar-

ent that any tendency of the counterweight to stick up will be overcome. The counterweight 34 will continue to fall by its own weight until it reaches the stop arm 52, and during this movement will rotate pinion 35 70 in the reverse direction and through the intermediate gears, the motor will be rotated in the direction of the arrow y. Although the escapement wheel 21 is prevented from moving in the reverse direction with the 75 motor shaft 11 because of the engagement of the radial side of a tooth 21¹ on the escapement wheel 21 with the outer edge of a tooth 30¹ of the pallet 30, the ratchet wheel 16 and pawls 22, however, permit the motor 80 shaft 11 to rotate in the reverse direction independently of the escapement wheel 21. As the pawls 22 are forced outward by the ratchet wheel 16 moving in the reverse direction, their outward movement is limited 85 by stop pins 67 on the escapement wheel 21.

Spring 47 also returns the pallet support 28 to its normal position, thereby bringing teeth 30¹ and 30² of the pallet 30 into engagement with teeth 21¹ of the escapement 90 wheel 21, and further acts as a means to steady the pallet in its normal position.

It will be seen by referring to Fig. 2, that pin 44 will move freely in the slot 45¹ of the link 45, as the counterweight 34 moves 95 downwardly, and by the action of the counterweight 56¹, contact carrier 56 will be rocked on its pivot pin 57 toward the left hand so that contact fingers 59 will break contact with contacts 64 and will again make 100 contact in a like manner quickly with contacts 61, thus completing a cycle of movements of the relay.

While I have shown and described a relay that is slow acting when it is energized, 105 it is apparent that, by a simple rearrangement or reversal of parts, which will in no way alter the functions or mode of operation, the relay may be changed into one that will be slow acting when deenergized. 110

Although I have particularly described the construction of one physical embodiment of my invention and explained the operation and principle thereof; nevertheless, I desire to have it understood that the form selected is merely illustrative, but does not exhaust the possible physical embodiments of the idea of means underlying my invention.

What I claim as new and desire to secure 120 by Letters Patent of the United States, is:

1. In a time element relay, in combination: a movable member, circuit controlling means operated by said member near one extreme of its movement, a motor for operating said member, an escapement wheel driven simultaneously with the movement of said member in one direction, a pallet adapted to coöperate with the escapement wheel, and means controlled by said member 125 130

- for moving the pallet out of engagement with the escapement wheel at a predetermined point near the above mentioned extreme of the movement of said member.
5. 2. In a time element relay of the type in which a movable circuit controlling element is automatically actuated from its normal position after a predetermined interval of time following a change in the energization 10 of the relay, the combination with the circuit controlling element, of a counterweighted member acting at one extreme of its movement to actuate said element, a motor and associated gearing for raising said counterweighted member, time controlled mechanism effective to regulate the rate of movement of said member in one direction, and means depending upon the movement of said member for rendering 15 said time controlled mechanism inactive at a predetermined position near one extreme of the movement of said member in said direction, whereby the timing action automatically ceases when the counterweighted member nearly attains its extreme position so as to permit quick operation of the circuit controlling element.
3. In a time element relay of the type in which a movable circuit controlling element 20 is automatically actuated from its normal position after a predetermined interval of time following a change in the energization of the relay, the combination with a rocking and counterweighted contact carrier constituting the circuit controlling element, of a movable member biased to one extreme position and acting at its other extreme position to move said contact carrier in opposition to its bias, adjustable means for determining the biased extreme position of said member, electro-responsive means for operating said member in opposition to its bias and time controlled mechanism operatively connected to said member for regulating 25 the rate of movement thereof from its biased position to its other extreme position.
4. In a time element relay, in combination: a movable member, circuit controlling means operated thereby, a motor for operating 30 said member, an escapement wheel driven in accordance with the movement of said member in one direction, a pallet adapted to coöperate with the escapement wheel, said pallet being movable into and 35 out of engagement with the escapement wheel, and means controlled by the member for moving and holding the pallet out of engagement with the escapement wheel during the latter part of the range of movement of said member in said direction.
5. In a time element relay of the type in which a movable circuit controlling element 40 is automatically actuated from its normal position after a predetermined interval of time following a change in the energization 45 of the relay, the combination with a biased contact carrier constituting the circuit controlling element, of a movable member biased to one extreme position and acting at its other extreme position to move said contact carrier in opposition to its bias, adjustable means for determining the biased extreme position of said member, electro-responsive means for operating said member in opposition to its bias and time controlled mechanism operatively connected to said member for regulating 50 the rate of movement thereof from its biased position to its other extreme position.
6. In a time element relay, in combination: a counterweighted member supported to move vertically, circuit controlling means 55 operated by said member, a motor for operating said member, an escapement wheel operatively connected to said member upon movement thereof in one direction, a pallet adapted to coöperate with said escapement wheel, said pallet being movable into and out of engagement with said escapement wheel, and means acting at a predetermined point in the movement of said member for moving said pallet out of engagement with the escapement wheel.
7. In a relay, in combination: a circuit closing means; a motor for operating said circuit closing means; a shaft operated by said motor; a pinion and a ratchet wheel 60 operated by said shaft; an escapement wheel loosely mounted on said shaft; pawls attached to said escapement wheel and adapted to engage with said ratchet wheel and drive said escapement wheel in one direction; a pallet for governing said escapement wheel; a support for said pallet; and means governed by the motor to operate said support after part of the movement of said motor to disengage said pallet from 65 said escapement wheel.
8. In a time element relay of the type in which a movable circuit controlling element is automatically actuated from its normal position after a predetermined interval of 70 time following a change in the energization of the relay, the combination with a contact carrier biased to one position and constituting the circuit controlling element; of a counterweighted member mounted to oscillate on a horizontal axis; means constituting an operating connection between said contact carrier and said member for causing said member, upon attaining one extreme position, to move said carrier in opposition to 75 its bias; a motor and associated gearing for raising said counterweighted member; and time controlled means for regulating the rate of movement of said member toward said extreme position, said time controlled means being automatically rendered inactive by said member after part of the movement thereof.
9. In a time element relay of the type in which a movable circuit controlling element 80

- is automatically actuated from its normal position after a predetermined interval of time following a change in the energization of the relay, the combination with a counter-
 5 weighted contact carrier constituting the circuit controlling element, of a counterweighted sector-gear mounted to oscillate on a horizontal axis and adapted upon attaining one extreme position to move said carrier in op-
 10 position to its bias, a motor and associated gearing connected to said sector-gear, adjustable means for determining the biased extreme position of said sector-gear, and timing means for regulating the rate of
 15 movement of said sector-gear toward its extreme position, said timing means being automatically rendered inactive by said sector-gear after part of the movement thereof.
 10. In a relay, in combination: a circuit
 20 closing means; a shaft for operating said means; a motor for operating said shaft; an escapement wheel operatively connected with said shaft when said shaft is rotating in one direction; a pallet having weighted
 25 arms; a movable pallet support; a spring to press said pallet down into engagement with said escapement wheel; and an adjustable stop to limit the downward movement of said pallet.
 30 11. In a relay, in combination: a circuit closing means; a shaft for operating said means; a motor for operating said shaft; an escapement wheel operatively connected with said shaft when said shaft is rotating in one
 35 direction; a pallet having weighted arms; and means to lift said pallet out of engagement with said escapement wheel after said shaft has made a predetermined movement.
 12. In a time element relay, in combina-
 40 tion: a counter-weighted member supported to move vertically, circuit controlling means operated by said member, a motor, gearing including an escapement wheel and a pawl and ratchet mechanism for operatively con-
 45 nnecting the motor and said member, a pallet adapted to coöperate with the escapement wheel, a support for said pallet, means for adjusting the range of movement of the pallet support, and means controlled by said
 50 member for operating said support.
 13. In a time element relay, in combina-
 55 tion: circuit controlling means biased to one position, a motor for operating said means in opposition to its bias, gearing including an escapement wheel and a pawl and ratchet mechanism for operatively connecting the motor and said circuit controlling means, a pallet adapted to coöperate with the escapement wheel, a movable support for the pallet
 60 which is spring-pressed to move the pallet into engagement with the teeth of the escapement wheel, and means controlled by said gearing for operating said pallet support.
 65 14. In a time element relay, in combina-
 tion: circuit controlling means biased to one position, a motor and associated gearing for operating the circuit controlling means in opposition to its bias, time controlled mech-
 70 anism for regulating the rate of movement of the motor and gearing, and means for rendering said mechanism inactive after a predetermined portion of the movement of the motor and its associated gearing.
 15. In a time element relay, in combina-
 75 tion: a movable member biased to one position, circuit controlling means operated by the member, means for adjusting the range of movement of said member, a motor for operating said member in opposition to its bias, time controlled mechanism for controlling the rate of movement of said member in one direction, and means controlled by said member for rendering the control of said mechanism ineffective at a predeter-
 80 mined point near one extreme in the range of movement of said member.
 16. In a time element relay, in combina-
 85 tion: a movable member biased to one ex-
 treme of its range of movement, a motor and associated gearing for driving the mem-
 ber to the other extreme, means for adjust-
 90 ing the range of movement of said member, time controlled mechanism effective for part of the movement of the member for regu-
 lating the rate of movement thereof in one direction, and circuit controlling means op-
 95 erated by the member at one extreme of its movement.
 17. In a time element relay, in combina-
 100 tion: a movable member, means for adjust-
 ing the range of movement of said member, timing mechanism effective to regulate the rate of movement of said member in one direction from its adjusted position to a pre-
 105 determined point near the opposite extreme, and circuit controlling means operated by said member near said extreme of its move-
 110 ment in said direction.
 18. In a time element relay, in combina-
 115 tion: circuit controlling means biased to one position, a counter-weighted member sup-
 ported to move vertically and adapted to operate the circuit controlling means near one extreme of the movement of said mem-
 ber, a motor for operating the member in opposition to its bias, and time controlled mechanism for regulating the rate of move-
 120 ment of said member and automatically con-
 trolled by said member to be effective for only part of the movement thereof toward said extreme.
 19. In a time element relay, in combina-
 125 tion: a counterweighted sector-gear mounted to oscillate on a horizontal axis, a motor, reduction gearing connecting said motor and said sector-gear, a counterweighted contact carrier, means adapted to establish an op-
 erative connection between said contact car-
 rier and the sector-gear and cause movement 130

- of the contact carrier in opposition to its bias only when the sector nearly attains one extreme position, and time controlled mechanism actuated by said sector-gear for regulating its movement toward said extreme position.
20. In a time element relay of the type in which there is an adjustable time interval between a change in the energization of the 10 relay and the operation of its circuit controlling element from its normal position, the combination with the circuit controlling element, of a counterweighted member adapted to actuate said element at one extreme position, and adjustable means for determining the other extreme position of said member, said means comprising an arm pivotally supported at one end and having its other end positioned to act as a stop for 15 the counterweighted member, together with an adjusting screw engaging said arm between its ends.
21. In a relay, in combination: a circuit controller biased to one circuit controlling 25 position and adapted to be operated to another position; a counterweighted member supported to move vertically from one extreme position to another extreme position; adjustable means for determining the initial 30 position of said member; a motor for operating said member; timing mechanism for governing the rate of movement of said member in one direction, said mechanism comprising an escapement wheel and a pallet having weighted arms; a movable support for said pallet; means for adjusting 35 said support to vary the extent of movement of said pallet; a lost motion device operatively connecting said circuit controller and 40 said member; and means associated with said movable member for lifting said pallet out of engagement with said escapement wheel at a predetermined point in the movement of said member.
- 45 22. In a time element relay, in combination: a counterweighted member supported to move vertically; a motor for driving said member; a circuit controller biased to one position and adapted to be operated to another 50 position by said member near one extreme of its movement; a lost motion device connecting said circuit controller and said member; adjustable means for determining the initial position of said member; a timing mechanism for governing the rate of movement of said member in one direction, said mechanism comprising an escapement wheel and a pallet, said pallet being movable bodily into and out of engagement 55 with said escapement wheel; and means controlled by said movable member for moving said pallet out of engagement with said escapement wheel at a predetermined point in the range of movement of said member.
- 60 65 23. In a time element relay, in combination: a circuit controller comprising a counterweighted contact carrier; a counterweighted gear sector supported to move vertically; a motor and gearing for operating said sector; a lost motion device operatively connecting said sector and said contact carrier; timing mechanism operated in accordance with the movement of said sector for controlling the rate of movement thereof, in one direction, said mechanism comprising an escapement wheel, a pallet, and a movable support for said pallet; and means actuated by said sector for moving said support to lift the pallet out of engagement with the escapement wheel at a predetermined point in the movement of said sector near its upper extreme.
24. In a time element relay, in combination: a circuit controller; means for operating said circuit controller from one extreme 85 position to another; timing mechanism for governing the rate of movement of said operating means, said mechanism comprising an escapement wheel and a pallet; and means for throwing said pallet out of engagement with said escapement wheel at a predetermined point in the range of movement of said operating means.
25. In a time element relay, in combination: a circuit controller biased to one position 95 and adapted to be operated to another position; operating means for said circuit controller including a counterweighted member supported to move vertically; timing mechanism for governing the rate of movement of said operating means, said mechanism comprising an escapement wheel and a pallet; means for adjusting said pallet relatively to said escapement wheel; and means operated by said counterweighted 100 member for throwing said pallet out of engagement with said escapement wheel at a predetermined point in the movement of said counterweighted member near its upper extreme.
26. In a time element relay, in combination: a contact carrier biased to one circuit controlling position and adapted to be operated to another position; a counterweighted gear sector supported to move 115 vertically; a lost motion device operatively connecting said contact carrier and said sector; a motor and associated gearing for driving said gear sector; an escapement wheel; a pawl and ratchet mechanism for 120 operatively connecting said escapement wheel and gear sector; a pallet adapted to coöperate with said escapement wheel; a movable support for said pallet; means for adjusting said support to vary the relative 125 distance between the axial centers of said pallet and said wheel; means controlled by said gear sector for moving said support to lift said pallet out of engagement with said escapement wheel after the gear sec- 130

tor has moved to a predetermined extent from its initial position; and adjustable means for determining the extent of travel of said gear sector from its initial position 5 to the point where said support is moved.

27. In a relay, the combination with a timing mechanism comprising an escapement wheel, a weighted pallet, and a movable support for said pallet adapted to be 10 adjusted to vary the distance between the axial centers of said escapement wheel and said pallet, of means controlled by said mechanism for moving said support to lift said pallet out of engagement with said escapement wheel.

28. In a time element relay, in combination: a circuit controller biased to one circuit controlling position and adapted to be operated to another position; a pivotally mounted counterweighted member; adjustable means for determining one extreme position of said member; a lost motion device operatively connecting said circuit controller and said member; a motor; gearing 20 operatively connecting said motor and said member; an escapement wheel; means for operatively connecting said escapement wheel and said member when the latter moves in one direction and for disconnecting 25 said parts for movement in the opposite direction; a pallet associated with said escapement wheel; a movable support for said pallet; and means acting at a predetermined point in the movement of said member for 30 moving said support to lift said pallet out of engagement with the escapement wheel.

29. A timing mechanism for relays comprising an escapement wheel and a pallet, said pallet being mounted on a movable 40 support which may be adjusted to vary the relative distance between the axial centers of said escapement wheel and said pallet and which may be operated to move the pallet bodily out of engagement with said escapement wheel, and means governed by 45 said timing mechanism for operating said pallet support.

30. In a time element relay, in combination: a movable member biased to one extreme of its range of movement, a motor 50 and associated gearing for driving the member to the other extreme, means for adjusting the range of movement of said member,

time controlled mechanism for regulating the rate of movement of said member in 55 one direction, a biased circuit controller, and means comprising a slotted link and pin for operatively connecting said circuit controller and said member near one extreme of the movement of said member to 60 cause movement of said circuit controller in opposition to its bias.

31. In a time element relay, in combination: a counterweighted member supported to move vertically; a motor for driving said 65 member; a circuit controller biased to one position and adapted to be operated to another position by said member near one extreme of its movement; a lost motion device connecting said circuit controller and said 70 member; adjustable means for determining the initial position of said member; and a timing mechanism for governing the rate of movement of said member in one direction.

32. In a time element relay, the combination with a circuit controller including a biased contact carrier, of operating means therefor comprising a pivotally mounted counterweighted member, a motor and gearing for raising said counterweighted member, adjustable means for determining the biased extreme position of said member, means adapted to establish an operative connection between the contact carrier and said counterweighted member near the upper extreme position of the latter, and timing mechanism including an escapement wheel and a pallet adjustable relatively to each other for regulating the rate of upward movement of said counterweighted member. 90

33. In a time element relay, in combination: a contact carrier biased to one circuit controlling position and adapted to be operated to another position; a counterweighted gear sector supported to move vertically; 95 a lost motion device operatively connecting said contact carrier and said sector; a motor and associated gearing for driving said gear sector; an escapement wheel; a pawl and ratchet mechanism for operatively connecting said escapement wheel and gear sector; a pallet adapted to coöperate with said escapement wheel; and adjustable means for determining the initial position of said gear sector. 100
